UNITED STATES PATENT OFFICE

FRANK O. DEGENHARDT, OF BROOKLYN, NEW YORK

GAME APPARATUS

Application filed December 13, 1930. Serial No. 502,024.

This invention relates to an improvement in a game apparatus designed particularly for use as a game for playing baseball indoors or in a relatively small space out of doors, the invention, however, being in no manner limited to a baseball game as the apparatus may be designed for similarly playing football or other well known games.

The particular type of game to which the invention relates is shown and described in Letters Patent No. 1,507,343, September 2nd, 1924, and similarly thereto, I preferably employ a baseboard depicting an umpire and catcher representative of the game employed in this form and which is adapted to be placed and maintained during play in a substantially vertical position against a wall or fence or in any other desired manner.

An aperture is provided in any suitable portion of the baseboard so that each particular play as made is designated therein to enable the respective players to record or keep the score applicable to the type of game being played.

Furthermore, in this form of the invention a ball or similar object is thrown against the baseboard to operate a controlling means, which automatically places an indicator in position to be readable through the aforementioned aperture. A plurality of such controlling mechanisms each having a different type of play associated with the same are positioned on the baseboard.

It has been found in the use of the invention described in the aforementioned Letters Patent that in the event the ball or object thrown by the player strikes a plunger extending through the baseboard indirectly or partially, the same will not have sufficient energy imparted to it to operate the indicator. Therefore, the principal object of my present invention is to provide a mechanism which eliminates this undesired characteristic. In so doing the plunger extending through the baseboard when actuated by the ball or object thrown against the board by the player is sensitively adjusted to facilitate the automatic and positive operation of a separate energized means for moving the indicator to a visible position.

A further object is to provide a mechanism whereby the player may readily return the indicator to an invisible position after the play has been recorded.

Other objects, advantages and novel features of design, construction and arrangement will be hereinafter apparent by reference to the accompanying drawings in which Figure 1 is a front elevation of the improved game apparatus. 55

Fig. 2 is an enlarged perspective view of one of the control mechanisms associated therewith, and 60

Fig. 3 is a rear elevation of the supporting plate showing the association of the various 65 units mounted thereon.

Referring to the drawings, and more particularly to Figure 1, the embodiment of the invention herein disclosed is incorporated in a baseboard 10 of a preferably rectangular shape and upon the surface of which is a representation of a catcher 11 and an umpire 12. The baseboard in playing the game may be suitably placed in a substantially vertical position against a wall when the game is played indoors or maintained in a like position against a fence, or otherwise, when the game is played out of doors. An aperture or opening 13 is provided in the upper portion of the baseboard 10 and preferably in a position indicating the mouth of the umpire 12 at which point a plurality of individually operable indicators are visible to designate a particular play as the same is made. Suitably secured to the rear of the baseboard 10 70 75 80 85

is a plate 14 upon which a plurality of individual controlling mechanisms are utilized as will be hereinafter more particularly described. 90

The plate 14 has a plurality of openings 95 therein, each of which is in alignment with an opening in the baseboard 10 to accommodate a like number of plungers 15 passing through the same. The forward end of each plunger has a button 16 which projects outwardly from the baseboard 10 and is adapted to be struck by the ball or other object thrown by the participants in the game. Each button is associated with a given type of play applicable to the kind of game to which the 100

invention is designed to illustrate. Inasmuch as each of the controlling mechanisms is essentially identical but one of the same will be described in detail.

Referring particularly to Fig. 2, an arm 17 connected to the plunger 15 pivotally maintains the same as indicated at 18 to a supporting bracket 19 fastened to the rear of the plate 14 in any suitable manner. Energized means yieldingly associated with the plunger, and herein illustrated in the form of a leaf spring 20, is connected to the plate 14 and is adapted to normally maintain the plunger 15 so that the button 16 is in an extending position from the baseboard 10 to be struck by the ball in playing the game. The side surface of the arm 17 presses against the surface of the plate 14 to determine the maximum forward position in which the spring 20 maintains the plunger. The bracket 19 also includes a lug 21 for limiting the backward pivotal movement of the arm 17 and which is adapted to form a stop so that a direct strike of the ball upon the button 16 will not move the plunger 15 sufficiently to injure the spring 20.

A catch or dog 22 is also connected to the yieldable plunger 15, the purpose of which will be hereinafter more particularly described.

Operatively associated with each mechanism is an integral rod 23 which is pivotally mounted on a suitable support 24 extending from the baseboard 10. The upper portion 35 of the rod carries an indicator 25 which is normally maintained in an invisible position behind the board. In the operation of the particular mechanism associated with a given indicator the same is moved to a position to be visible through the opening 13 at the mouth of the umpire as indicated at 26.

The lower or opposite portion of the rod 23 extends downwardly adjacent to the plunger 15 and is adapted to be normally maintained in this position by the catch or dog 22 controlled by the spring 20. A second energized means, illustrated in the form of a spring 27, is connected to the lower portion of the rod and the baseboard in any desired manner so that the same is operatively associated with said rod to swing the indicator to a visible position when the plunger 15 is actuated to release the engagement between the rod and catch as indicated by the dotted lines in Fig. 2. In this manner a sensitive mechanism is provided which insures the movement of the indicator to a visible position regardless of the manner in which the ball or other object strikes the button 16.

The relationship of the individual mechanisms as positioned on the rear of the plate 14 is clearly illustrated in Fig. 3. Suitable guides are provided in the upper portion of the plate as indicated at 28 to control the movement of the rods 23 therein. A centrally

located stop 29 limits the movement of the rods 23 when actuated by the spring 27 so that the indicator 25 is visible through the opening or slit 13 in the baseboard. A rod 30 is pivotally connected to the end of the lower portion of the rod 23 as indicated at 31 and is slidingly maintained in a bracket 32 or other suitable means located on the rear edge of the baseboard 10. The ends of the respective rods 30 are provided with knobs 33. These knobs are visible to the players from the front of the board as illustrated in Fig. 1 and make it readily apparent from their respective positions which mechanism has been actuated inasmuch as the knob for this particular mechanism will be located nearer the edge of the baseboard 10 than the others as indicated at 34. By manually pulling the rod 30 outwardly the rod 23 is returned to its normal position adjacent the plunger 15 and secured thereby by the catch 22 to automatically withdraw the indicator from its visible position.

In playing the game any number of participants can be accommodated in groupings of individuals or teams as desired, each player in turn being permitted to throw a predetermined number of balls at the baseboard 10 with the purpose of operating the plunger that will facilitate the setting of the indicator having the most advantageous play thereon in a visible position. The slightest energy imparted to the button 16 will pivot the plunger 15 against the action of the spring 20 so that the dog or catch 22 releases the rod 23 which is separately actuated by means of the spring 27 to move the indicator to a visible position to the rear of the opening 13 in the mouth of the umpire. After the play indicated has been recorded the knob 33 closest to the baseboard 10 is manually pulled to return the indicator to an invisible position and set the mechanism so that play can thereafter be resumed.

The particular type of play applicable to the game illustrated in this instance relates to baseball, although obviously other games may be utilized for play in the same manner without departing from the nature and spirit of the invention.

I claim as my invention:

1. In a game apparatus, a baseboard, a plunger extending through the same, an indicator, a rod to which at one end the indicator is attached, a support extending from said baseboard and to which the rod is pivotally connected to swing the indicator from an invisible to a visible position, means associated with said plunger to yieldingly engage a portion of the opposite end of said rod and to normally maintain the indicator in an invisible position, energized means associated with the last named portion of said rod whereby on the release of said first named

means the same is pivoted to swing the indicator to a visible position.

2. In a game apparatus, a baseboard, a plunger extending through the same, an indicator, a rod to which at one end the indicator is attached, a support extending from said baseboard and to which the rod is pivotally connected to swing the indicator from an invisible to a visible position, a catch associated with said plunger to yieldingly engage a portion of the opposite end of said rod and to normally maintain the indicator in an invisible position, energized means associated with said last named portion of said rod whereby on the release of said catch the same is pivoted to swing the indicator to a visible position.
3. In a game apparatus, a baseboard, a plunger extending through the same, an indicator, a rod to which at one end the indicator is attached, a support extending from said baseboard and to which the rod is pivotally connected to swing the indicator from an invisible to a visible position, means associated with said plunger to yieldingly engage a portion of the opposite end of said rod and to normally maintain the indicator in an invisible position, energized means associated with the last named portion of said rod whereby on the release of said first named means the same is pivoted to swing the indicator to a visible position, and means associated with said rod whereby the same is manually returnable to its normal position.
4. In a game apparatus, a baseboard, a plunger extending through the same, an indicator, a rod to which at one end the indicator is attached, a support extending from said baseboard and to which the rod is pivotally connected to swing the indicator from an invisible to a visible position, a catch associated with said plunger to yieldingly engage a portion of the opposite end of said rod and to normally maintain the indicator in an invisible position, energized means associated with said last named portion of said rod whereby on the release of said catch the same is pivoted to swing the indicator to a visible position, means pivotally connected to the end of said rod whereby the same is manually returnable to its normal position.
5. In a game apparatus, a baseboard, a plunger extending through the baseboard and pivotally associated therewith, a catch located on said plunger, an indicator, a rod to which at one end the indicator is attached, a support extending from the baseboard and to which the said rod is pivotally connected to swing the indicator from an invisible to a visible position, energized means associated with the plunger to normally maintain said catch in engagement with a portion of the opposite end of said rod thereby holding the indicator in an invisible position, and means pivotally connected to the end of said rod whereby the indicator is manually returnable to its normal invisible position.
6. In a game apparatus, a baseboard, a

plunger extending through the baseboard and pivotally mounted thereon, a catch located on said plunger, an indicator, a rod to which at one end the indicator is attached, a support extending from the baseboard and to which the said rod is pivotally connected to swing the indicator from an invisible to visible position, energized means associated with the plunger to normally maintain said catch in engagement with a portion of the opposite end of said rod thereby holding the indicator in an invisible position, and a stop associated with said pivotal plunger for limiting the movement of the same.

7. In a game apparatus, a baseboard representing a player and having an aperture therein, a plunger extending through the baseboard and pivotally mounted thereon, a catch located on said plunger, an indicator, a rod to which at one end the indicator is attached, a support extending from the baseboard and to which the said rod is pivotally connected to swing the indicator from an invisible to a visible position behind the aperture, energized means yieldingly associated with said plunger to normally maintain said catch in engagement with a portion of the opposite end of said rod thereby holding the indicator in an invisible position, energized means operatively associated with said rod to swing the indicator to a visible position behind the aperture when the said plunger is actuated to release the engagement between the said rod and catch.

8. In a game apparatus, a baseboard representing a player and having an aperture therein, a plunger extending through the baseboard and pivotally mounted thereon, a catch located on said plunger, an indicator, a rod to which at one end the indicator is attached, a support extending from the baseboard and to which the said rod is pivotally connected to swing the indicator from an invisible to a visible position behind the aperture, energized means yieldingly associated with said plunger to normally maintain said catch in engagement with a portion of the opposite end of said rod thereby holding the indicator in an invisible position, energized means operatively associated with said rod to swing the indicator to a visible position behind the aperture when the said plunger is actuated to release the engagement between the said rod and catch, and means pivotally connected to the end of said rod whereby the indicator is manually returnable to its normal invisible position.

Signed by me this 9th day of December, 1930.

FRANK O. DEGENHARDT.
